DESIGN FOR A PORTABLE MOTOR-DRIVEN SAW

Paul Schildknecht, Los Angeles, Calif., assignor
of one-half to Thomas Graning, Los Angeles,
Calif.

Application June 29, 1946, Serial No. 131,200

Term of patent 14 years

(Cl. D93—3)

To all whom it may concern:

Be it known that I, Paul Schildknecht, a citizen of the United States, residing at Los Angeles, in the county of Los Angeles and State of California, have invented a new, original, and ornamental Design for a Portable Motor-Driven Saw, of which the following is a specification, reference being had to the accompanying drawing, forming part thereof.

In the drawing:

Fig. 1 is a perspective view of a portable motor-driven saw showing my new design;

Fig. 2 is a top plan view of the portable motor-driven saw; and

Fig. 3 is an end elevation looking in the direction of the arrow 3 of Figure 2.

I claim:

The ornamental design for a portable motor-driven saw, as shown.

PAUL SCHILDKNECHT.
